UNITED STATES PATENT OFFICE.

LOUIS B. SMYSER, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

CASEMENT-WINDOW OPERATOR.

1,095,682.

Specification of Letters Patent.

Patented May 5, 1914.

Application filed October 1, 1913. Serial No. 792,766.

To all whom it may concern:

Be it known that I, LOUIS B. SMYSER, a citizen of the United States, and a resident of New Britain, in the county of Hartford and State of Connecticut, have invented 5 certain new and useful Improvements in Casement-Window Operators, of which the following is a specification.

This invention relates particularly to certain 10 improvements in casement window operators, the particular object of the invention being to provide a mechanism of the character described, all parts of which shall be substantially concealed in the window frame or beneath the window sash, and in 15 which the parts actuating the sash are free from interference with other parts of the window structure, such as the screen which is usually placed inside of the sash.

20 The invention also embodies certain details of construction which are particularly advantageous.

In the drawings—Figure 1 is a view of an operating mechanism made in accordance 25 with my invention, installed ready for use, a portion of the sill being broken away to show the arrangement of the parts. Fig. 2 is a cross sectional view of a portion of a typical window construction, and showing 30 the installation of the mechanism. Fig. 3 is a group view showing the various parts of the mechanism detached. Fig. 4 is a plan view of the mechanism assembled ready for installation.

35 In the drawings, *a* denotes generally the window frame, and *b* the sill within which the operating mechanism is located; *c* is the sash carried as usual on suitable vertical hinge supports; *d* represents a screen positioned 40 inside the sash; *e* denotes an operating shaft extending from the mechanism to the inside of the frame and having an operating handle *f*, by means of which the sash can be moved through the mechanism without 45 moving, disturbing or working through the screen or any other device which may be located in the frame inside of the sash.

The operating mechanism comprises a housing *1*, located in a recess in the frame and held in position as by the screws *2*. The housing is chambered in its upper face, as at 5, and transversely apertured as at 6. This aperture opens into the chamber in order that a gear in the chamber may mesh

with a pinion located in this transverse aperture. Within the chamber is located a gear 10 preferably of the worm type, seated in a proper bearing in the bottom of the chamber and supported at its upper side in the annular cover *7*, which closes the chamber but permits of effecting a driving connection with the gear. The transverse aperture is enlarged at one side of the housing to permit of the entrance of the pinion *15*, one end of the shaft, *16*, being supported in the wall 65 of the housing as at 3, the other end of the shaft, *17*, being supported in the bushing *20* fitting within the enlarged aperture. Both ends of the shaft are exposed and have squared sockets to receive the operating 70 shaft *e*, in order that the same housing may be used either for a right or left hand sash. The bushing is held in position by the taper pin *21*. The sleeve *25* has a reduced end *26*, fitting within the aperture in the cover, and 75 a fin *27* which may be driven down into the sill to prevent the rotation of the sleeve. This sleeve provides a bearing for the connector *30*, which at its lower end has a driving engagement with the gear *10*, and at its 80 upper end with an actuating lever *35*, where it fits within an aperture *36* in the lever, which aperture is traversed by a cross web *37* which fits within a groove *31* in the upper end of the connector. The other end of the 85 lever is provided with a stud *38* upon which is mounted a roller *39*, which travels in a slot *40* in the plate *41* which is fastened to the underside of the sash.

By reference to Figs. 1 and 2 it will be 90 seen that the axis of the gear and connector is preferably located centrally of the width of the sash and close to the axial line of swing thereof in order that as the sash is swung by the lever the latter is substantially 95 concealed from view in all positions of the sash, and when the sash is closed the lever is wholly concealed from view. This also permits of wholly concealing the operating mechanism by locating it in a recess in the 100 frame, and of carrying the operating shaft through the lower part of the frame to the inner side thereof, where it is provided with a small operating handle fitted closely to the frame within the room, although of 105 course it is apparent that where the frame is covered, as by a radiator or other device, the operating shaft *e* can be extended so

that the handle can be placed in any convenient position.

The use of the worm wheel and pinion is preferred since it provides a lock for the 5 sash in any position of adjustment.

The housing is closed at its lower end in order that the chamber may also act as a reservoir for lubricant, the connector being provided with an oil hole 33 and outlets 34.

10 The complete operating mechanism is very compact; the construction avoids the necessity of making separate housings for right and left hand sashes; it is susceptible of economical manufacture, and is extremely 15 efficient in its operation. The use of the connector permits of adapting the principal parts of the mechanism to varying conditions by the substitution of connectors of different lengths.

20 I am aware that the structure herein illustrated and described is susceptible of various modifications and alterations without departing from the spirit of the invention as set forth in the appended claims. Also, 25 that the use of this mechanism is not necessarily limited to casement windows, but can be adapted for use with other structures of a similar character.

I claim as my invention:—

30 1. The combination with a window frame or the like and a swinging closure therefor, of a housing located in a recess in the sill of said frame, a chamber formed in the upper side of said housing, a gear mounted 35 therein, an annular cover for said chamber, a sleeve seated at its lower end in said cover, a connector supported by said sleeve and having a driving engagement with said gear, an actuating lever in driving engagement 40 with the upper end of said connector, operative connections between said lever and closure, a pinion mounted in said housing in mesh with said gear, and an operating shaft therefor.

45 2. The combination with a framed opening and a closure therefor mounted to swing on vertical hinge supports, of an operating mechanism for said closure, comprising a housing located in a recess in the bottom of 50 the framed opening, a gear mounted therein on a vertical axis located at approximately the central plane of the closure, an actuating lever operatively connected with the closure, a connector interposed between 55 and having driving engagement with said lever and gear and non-integral with either, a pinion mounted in said housing in mesh with said gear, and an operating shaft for

said pinion extending to the inside of said framed opening.

60

3. In an operating mechanism of the character described, a housing, a pair of intermeshing gears located therein, an actuating lever, a connector interposed between and having driving engagement with said lever 65 and with one of said gears and non-integral with either, and a sleeve within which said connector fits and has its bearing.

4. In an operating mechanism of the character described, a housing having a chamber in its upper side, a gear located in the chamber, an annular cover for said housing forming a bearing for the upper side of said gear, a separate sleeve having a reduced end fitting within said cover and forming a 75 shoulder resting thereon, a connector fitting and having a bearing in said sleeve, a driving engagement between said connector and gear, a lever in driving engagement with the upper end of said connector, and means 80 for fastening together said lever, connector, sleeve, gear and cover.

5. An operating mechanism of the character described, including a housing having a chamber in the upper side thereof and a 85 transverse aperture enlarged in one wall of said housing, a gear mounted in said chamber, a pinion mounted in said aperture in mesh with said gear, a pinion shaft having one end located in the aperture in one wall 90 of the housing, a bushing located in the enlarged aperture in the other wall of the housing and constituting a bearing for the opposite end of the pinion shaft, an end of said pinion shaft being exposed and adapted 95 for driving connection with an operating shaft.

6. An operating mechanism of the character described, including a housing provided with a chamber in its upper side and 100 a gear mounted therein, a transverse aperture in the housing communicating with said chamber, a pinion mounted therein in mesh with said gear, a stub shaft at either end of said pinion, one of said shafts being adapted 105 to take a bearing in the aperture in one wall of the housing, a bushing fitted in the enlarged aperture in the opposite wall of the housing and providing a bearing for the shaft at the other end of the pinion, and 110 means for securing said bushing in place.

LOUIS B. SMYSER.
